[57] **ABSTRACT**

A calculating rule comprises three coaxial cylindrical elements displaceable relative to one another by rotation. The outer cylinder has at least one transparent window and the intermediate cylinder is transparent. Each cylinder carries an index line serving as a reference line or carrying graduations. At least one of the index lines is helicoidal so that one index line intersects the two others at an angle different to 90°. Preferably, rotation of the intermediate cylinder relative to the outer one causes automatic rotation of the inner cylinder, but not vice versa. At least one of the elements can be planar.

CALCULATING RULE

This invention relates to calculating rules. According to the main aspect of the invention, there is provided a calculating rule comprising three superposed elements displaceable relative to one another: an upper element having at least one transparent window, a transparent intermediate element, and a lower element; each element carrying an index line, at least one of the index lines carrying a graduated scale and at least one index line serving as a reference line, one of the index lines being arranged to intersect the two other index lines at an angle different to 90°, the points of intersection of the index lines being visible through said at least one window, and relative displacement of the elements causing displacement of the points of intersection of the index lines.

In a preferred embodiment of calculating rule, the three elements are coaxial cylinders displaceable relative to one another by rotation.

The accompanying drawings show, schematically and by way of example, an embodiment of calculating rule according to the invention, as well as three variants thereof. In the drawings:

FIG. 1 is a schematic perspective elevational view of a calculating rule.

FIG. 2 is a partial expanded view of the cylinders composing the rule.

FIG. 3 is a cross-section, on enlarged scale, through one of the ends of this rule.

FIGS. 4 and 5 are partial enlarged diagrammatic views of two modified embodiments; and

FIG. 6 is a partial enlarged diagrammatic view of a third modified embodiment.

The principle of this calculating rule is to use three support elements 1, 2, 3 displaceable relative to one another, these support elements being superposed, at least the intermediate element 2 being transparent and the external or upper element 3 having at least one transparent window. Each support element 1, 2, 3 carries an index line A, B, C respectively, at least one of the index lines being a reference line, for example A and B in FIG. 2, and at least one of the index lines including a graduated scale, for example C in FIG. 2. At least one of the index lines is traced in a manner to cross the two others at an angle different to 90°, so that reading of values can take place by locating the point of intersection of the lines A, B, C.

The calculating rule shown in FIGS. 1, 2 and 3 comprises three concentric hollow cylindrical tubes relatively rotatable in relation to one another, the tubes 1 and 2 each carrying helicoidal reference line A, B respectively. The intermediate tube 2 is made of a transparent material. A transparent rectilinear slot is provided in the opaque external tube 3, so as to form a window 7 provided with a logarithmically graduated scale C. The setting of values takes place by adjusting the points of intersection of the helicoidal lines A and B with the logarithmic scale C by relative displacement of the appropriate tubes. These points of intersection are visible through the window 7.

Referring to FIG. 3, the inner tube 1 comprises a shoulder 4 by means of which a slight friction is obtained between itself and the median tube 2. On the median tube 2 is mounted a ring 5 fixed by a screw. This ring enables regulation of the frictional force

between the median tube 2 and the outer tube 3, by means of an elastic washer 6 on the latter. The frictional force obtained between the two tubes 3 and 2 is arranged to be greater than that between the tubes 2 and 1. Hence, rotation of the tube 1 does not cause rotation of the tube 2 when the tube 3 is held, whilst rotation of the tube 2 automatically causes rotation of the tube 1. The relative angular position between the tube 1 and the tube 2 will thus not be modified by the rotation of the tube 2 in relation to the tube 3. There is thus established a ratio of values which will be constant.

The external tube 3 provided with the transparent window 7 serves as a support for the assembly. The inner tube 1 is preferably provided in an opaque material, for example a white material.

The helicoidal reference lines A and B inscribed on the tubes 1 and 2 are of different colors, for example red and blue respectively.

Operation of the calculating rule will be described by giving an example of the execution of a multiplication operation, namely the multiplication 7.5×2.35 .

By rotation of the median tube 2, the blue helicoidal line B is displaced until it intersects the logarithmic scale C at the value (7.5) of the multiplicand. By rotation of the inner tube 1, the red helicoidal line A is then brought until it intersects the logarithmic scale C at the value 1 or 10. During this second operation, the blue helicoidal line B remains at the set value 7.5 so that there has thus been established a ratio (7.5/1) which will not be modified by further rotation of the median tube 2, which rotates the inner tube 1 with it. It then suffices to bring the red helicoidal line A onto the multiplicator (2.35) by rotation of the median tube 2. The result (17.62 ...) is read at the intersection of the blue helicoidal line B with the logarithmic scale C.

Divisions take place by proceeding in the same manner, but in the reverse order.

FIG. 4 is a partial expanded diagrammatic view of a modification having the same basic constructional features as before, by comprising two parallel helicoidal logarithmic scales D and E which are traced on the tubes 1 and 2, their relative position being located by the intersection with a reference line F inscribed longitudinally on the outer tube 3.

FIG. 5 is a partial expanded diagrammatic view of a second modification having the same basic constructional features as before, but comprising two parallel logarithmic scales inscribed in the longitudinal direction along two tubes 1 and 2, their relative position being located by the intersection of a helicoidal reference line I inscribed on the exterior tube 3. It is advantageous in this embodiment for the outer tube 3 to be transparent; alternatively an oblique window 7 could be provided.

FIG. 6 is a partial expanded diagrammatic view of a third modification having the same basic constructional features as before, but comprising two reference lines J and K of generally helicoidal shape, traced according to a logarithmic function of imaginary linear scales on the tubes 1 and 2. The relative position of lines J and K is determined by their points of intersection with a linear scale C inscribed along the exterior tube 3.

Operation of the modification shown in FIGS. 4, 5 and 6 takes place in an analogous manner to that for

the main embodiment shown in FIGS. 1, 2 and 3; in each case a constant ratio of values is set up, and this ratio is "displaced" by rotating the tube 2.

With reference to FIG. 4, the diagram illustrates obtaining the result of a multiplication such as $2.20 \times 2.35 = 5.17$.

To carry out such a multiplication, scale E is a first turned so as to have its index mark 1 coincide with line F, and scale D is shifted to bring its graduation 2.20 to coincide with line F. The two scales are then moved together until the graduation 2.35 of scale E intersects line F as illustrated in FIG. 4. The result 5.17 is given by the intersection of scale D with line F.

FIG. 5 illustrates the operation $2 \times 2.5 = 5$. To carry out this operation, the 1 of graduation G is first made to coincide with line I, and graduation H is then moved to bring 2.5 to coincide with line I. The two scales G and H are then moved simultaneously until the 2 of scale G coincides with line I, and the result of the operation is given by the intersection of line I with scale H.

In the case of FIG. 6, line K is moved so as to intersect scale L at its graduation 1, while line J is moved so as to intersect it at graduation 2. The two lines J and K are then moved together in the position illustrated in FIG. 6 to obtain the multiplication of the first factor (2) by the second factor (3) which is given by the intersection of line K with scale L. The result (6) of the operation is given by the intersection of line J with scale L.

It would also be possible to use the same system for a calculating rule with parallel support surfaces displaceable relative to one another instead of concentric tubes. For example, planar, spherical, or other surfaces having the characteristics shown in figs. 2, 4, 5 or 6 could be used.

One of the advantages of the new type of calculating rule described above resides in that it can be incorporated with virtually any cylindrical object such as a pencil, pen, tool handle, and so on. For example, the outer tube 3 could be formed by the body of a pen, or by the outer coating of a tool handle.

To facilitate reading, even in obscure conditions, a luminous source could be provided inside the inner cylinder 1 which could be made in transparent or translucent material. Of course, the window 7 could be provided with a magnifying glass to facilitate reading.

In the case where such a calculating rule was inserted, for example, in an automobile vehicle dashboard or aircraft control panel only the window 7 would be visible thereon; the external cylinder 3 being replaced by a simple plate placed against the dashboard or control panel. Knobs fixed to the cylinders 1 and 2 and protruding through openings in the dashboard or control panel would enable manipulation of the rule.

As a further modification, all three index lines could be helicoidal, one index line spiralling in one sense, and the other two in the other sense, for example.

I claim:

1. A calculating rule comprising three tubular support elements which are superposed and displaceable relative to one another, a reference line on each element, at least one of said reference lines including a graduated scale, the external element having at least one transparent window, the intermediate element

being made of transparent material, at least one of the reference lines being drawn in a manner to cross the other two reference lines at an angle other than 90° , so that reading of values can take place by locating the point of intersection of the lines, first friction means between the inner element and the intermediate element, second friction means between the intermediate element and the external element, the frictional torque exerted by the first friction means being less than the torque exerted by said second friction means, in such a manner that rotation of the inner element does not cause rotation of the intermediate element when the external element is fixed, while rotation of the intermediate element automatically causes rotation of the inner element, the relative angular position between the inner element and the intermediate element remaining unchanged by the rotation of the intermediate element.

2. A calculating rule as claimed in claim 1, in which the intermediate element and the inner element each carry a rectilinear reference line parallel to the axis of the elements, the said rectilinear reference lines each being provided with a logarithmically graduated scale, and the external element carries a helicoidal reference line.

3. A calculating rule as claimed in claim 2, in which the external element is transparent.

4. A calculating rule as claimed in claim 1, in which the external element carries a rectilinear reference line parallel to the axis of the elements and provided with a linear graduation, the intermediate and inner elements each carrying a reference line according to a logarithmic function of the said linear graduation.

5. A calculating rule as claimed in claim 1 wherein, the reference lines on said intermediate element and inner element each have helicoidal reference lines which are provided with logarithmically graduated scales and the window of said external element is rectilinear and parallel to the axis of said elements.

6. A calculating rule comprising three support elements which are superposed and displaceable relative to one another at least two of said elements being tubular, a reference line on each element, at least one of said reference lines including a graduated scale, the external element having at least one transparent window, the intermediate element being made of transparent material, at least one of the reference lines being drawn in a manner to cross the other two reference lines at an angle other than 90° , so that reading of values can take place by locating the point of intersection of the lines, first friction means between the inner element and the intermediate element, second friction means between the intermediate element and the external element, the frictional torque exerted by the first friction means being less than the torque exerted by said second friction means, in such a manner that rotation of the inner element does not cause rotation of the intermediate element with the external element being maintained fixed, while rotation of the intermediate element automatically causes rotation of the inner element, the relative angular position between the inner element and the intermediate element remaining unchanged by the rotation of the intermediate element.
